UNITED STATES PATENT OFFICE.

FERDINAND THIELKE, OF BROOKLYN, NEW YORK.

DESIGN FOR A HANDLE FOR BUTTON-HOOKS, &c.

SPECIFICATION forming part of Design No. 27,090, dated May 25, 1897.

Application filed April 9, 1897. Serial No. 631,450. Term of patent 31 years.

To all whom it may concern:

Be it known that I, FERDINAND THIELKE, a citizen of the United States, residing at Brooklyn, in the county of Kings and State of New York, have invented and produced a new and original Design for Handles for Button-Hooks and Like Articles, of which the following is a specification, reference being had to the accompanying drawing, which shows a side view 10 of my newly-designed handle applied to a button-hook.

The leading feature of my design consists of the general outline or contour of the handle, consisting of compound curves and forming three oval-shaped portions, the central field of the upper portion being plain and the other two portions decorated with scrolls. 15

Referring to the drawing, A represents the handle of the button-hook or other like article, the upper end being ornamented, as shown 20 at B. The handle has the outline shown, forming the oval-shaped portions C D E, the central field of the portion C being left plain and the edges decorated, as at a. The portion D carries the scrollwork b and the portion 25 E the scrollwork c.

What I claim is—

The design for a handle for button-hooks, and similar articles, substantially as herein shown and described.

FERDINAND THIELKE.

Witnesses:

GEO. S. CLARK,
AUGUST SOFFEL.
